FOUR-IN-HAND NECKTIE

Morris Schwartz, New York, N. Y.

Application August 14, 1947, Serial No. 768,568

10 Claims. (Cl. 2—146)

1

This invention relates to new and useful improvements in neckties of the four-in-hand type.

The prime object of the invention is to provide a necktie of this kind which may be manufactured without stitches for joining the infolded side sections along the broader end of the necktie from the tip of the latter up to or almost up to the neckband portion of the tie. The principle of the invention may be applied to the smaller end of the tie; but the advantages contemplated are of most striking value in the case of the broader end of the tie.

According to the invention, in the case either of a tie to be made from a single blank or to be made from a plurality of blanks cut so that they may be preliminarily stitched together end to end within the limits of what is to be the neck band portion of the tie when completed, the tie blank portion which is to be infolded along its sides to provide the plural-ply broader end of the tie is cut along its two free side edges to provide along one of said side edges a plurality of stepped parts and to provide along the other of its said side edges a plurality of oppositely located stepped parts.

These stepped parts are so proportioned and arranged that, when the usual infoldings at the sides of the tie are made, one of said stepped parts on one of such infoldings is interfoldable with that one of said stepped parts oppositely presented by the other of said infoldings, and another of said stepped parts on the last mentioned infolding is interfoldable with that one of said stepped parts oppositely presented by the other of said infoldings.

An important feature of the invention is that, in the case of each pair of oppositely presented stepped parts to be interfolded, such pair of stepped parts is so present that one of said stepped parts constitutes what may be termed a female structure or receptor for the opposite stepped part, so that the latter acts as a male element relative to such receptor; and, at the same time, pairs of oppositely matching stepped parts are so present that the receptor for one of said pairs and the male element for an adjoining one of said pairs are carried by one of said infoldings, while the respectively complementary male element and receptor are carried by the other of said infoldings. Thus a plurality of oppositely restrained locking pairs are provided; and the conjoint action of these pairs makes each locking pair properly characterizable as an interlocking means.

As a result, when the tie is pressed the pairs

2

of stepped and interlocking parts, interfolded pursuant to the invention, lock the broader end of the tie to its intended spread; but nevertheless, when the tie becomes wrinkled and so needs repressing, it may be opened from the back, repressed and folded as before. In this way wrinkles can be pressed out perfectly and with a minimum of time and expense.

If desired, auxiliary means, such as snap fasteners or the like, may be used to detachably couple the interfolded stepped parts. These fasteners, if used, preferably are so placed that there is ample room for the use of a regular iron in pressing.

15 A further feature of the invention is the provision of a plurality of blanks so shaped that one, which may be called the main blank, provides the broader end of the tie and a part of the neck band, and the other, which may be called the minor blank, provides the narrower end of the tie and a part of the neck band; whereby waste of the rich and expensive material from which fine ties are made may be minimized, and yet the aforesaid plurality of stepped parts may be present.

Still a further feature of the invention is an arrangement of said stepped parts relative to the other portions of the pair of blanks just referred to, such that one such pair of blanks after another may be so cut from a length of cloth, with one of said pairs immediately alongside of and interfitting with another thereof that there is no waste of material at all between any two adjoining pairs.

30 35 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 shows a length of cloth from which the tie is to be made, illustrating lines of cut to be effected to provide three pairs of sets of main and minor blanks.

Fig. 2 shows one of said sets of main and minor blanks, with these joined at their intended mating edges.

50 Fig. 3 is a fragmentary perspective view, showing the broader end of the tie to be made from such joined blanks by the interfoldings referred to.

Fig. 4 is an enlarged section, taken as it were on the line 4—4 of Fig. 3, but showing certain of

the folded portions further advanced toward final positions than in Fig. 3.

Fig. 5 is a similar view, but one taken as it were on the line 5—5 of Fig. 3.

Fig. 6 is a section, taken also as it were on the line 4—4 of Fig. 3, but showing the folded portions of Fig. 4 in their final positions.

Fig. 7 is a similar view, but one taken as it were on the line 5—5 of Fig. 3; that is, illustrating the folded portions of Fig. 5 in their final positions.

In Fig. 1 there is shown a length of fabric 10, of a selected design (not shown), selvaged along both opposite sides 11 and 12, and of a width such that a plurality of pairs of main and minor blanks, each such pair for the making of one tie, may be cut from the fabric 10, without other waste than that inconsiderable amount indicated at 14.

In order to make very plain the repeat pattern employed three such repeats are illustrated; and to make the drawing readily understood at first glance, the pattern at the left in Fig. 1 is comparatively heavily outlined. Cutting out this repeat provides a single piece 15; and cutting along the broken line 16 divides the piece 15 into a main blank 17 and a minor blank 18. The short cuts or slits 20 and 21 are also made.

The edge A—B of the minor blank 18 is of the same length as the edge C—D of the main blank 17; so that these two blanks may be matched end to end and seamed together as indicated at 22 in Fig. 2, thereby to make up the blank or body for the entire tie as there shown.

In Fig. 2 lines of fold only at the broad end of the tie are indicated, and only three of these, which three are marked 23, 24 and 25. At the left side of this view, above the fold line 23, and opposite the fold line 25, that side of the blank is stepped in to provide one of the aforesaid stepped parts; and above said stepped part, the same side of the blank is further stepped in, to provide another of the aforesaid stepped parts. At the right side of Fig. 2, above the fold line 24, that side of the blank also is stepped in, to provide still another of the aforesaid stepped parts.

Referring to Figs. 2—7, the fold made on the line 23 provides a flap 26, which, with the adjoining flap 27, provides a receptor for the marginal length 29 of the infolding 30; said length 29, of a width determined by the length of the slit 20, providing the male element for entering the receptor 28 to become finally interfolded therewith as shown in Fig. 6.

The fold made on the line 25 provides a flap 31, which, with the adjoining infolding 32, provides a receptor 33. The male element for entering this receptor, to become interfolded therewith as shown in Fig. 7, is provided by the flap 34, which latter is produced as the result of folding along the line 24. The outer face of the tie is provided by the central portion 35 of the blank. In the annexed claims, said central portion 35 will be referred to as the face panel, and said infoldings 30 and 32 will be referred to as the side or back panels.

The hereinabove mentioned snap fasteners for the interfoldings illustrated in Fig. 6 are shown at 36 as carried by the flap 26 and by the marginal length 29 of the infolding, or back panel, 30, and such fasteners for the interfoldings illustrated in Fig. 7 are shown at 37 as carried by the flap 31 and by the flap 34. As will be understood, the respectively matching pairs of snap fasteners will be one of the post type and the other of the socket type; these two types employed, for in-

stance, as indicated in Fig. 4, where the marginal length 29 of the back panel 30 is shown as carrying a post type fastener, and as indicated in Fig. 5, where the flap 34 is shown as carrying a post type fastener.

The infoldings or back panels 30 and 32 are continued above the flaps 31 and 34 up along the neck band, and there stitched in place in the usual or any desired way; and they are continued on to form at the portion 38 at the upper end of the blank 17—18 of Fig. 2 the narrow end of the tie. There said panels 30 and 32 are stitched in place in the usual or any desired way, or by one or more interfoldings of stepped parts according to the principles of the invention as explained in connection with the broader end of the tie.

A lining for the tie is not shown; but such a lining, whether of the now favored type involving the insertion of a suitably secured resilient strip of bias-cut and hence stretchable lining material, or otherwise, may of course be added.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped part of the other panel laterally of the tie whereby there are stepped parts in pairs across the width of the tie, said stepped parts being so proportioned and arranged and said back panels being so additionally relatively folded lengthwise of the tie that along a portion of the length the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, and said second interlocking means incorporating a receptor established by a fold lengthwise of said second back panel and said second interlocking means also incorporating a complementary male element for entry into the last-named receptor, the last-named male element forming a part of said first back panel.

2. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped part of the other panel laterally of the tie whereby there

are stepped parts in pairs across the width of the tie, said stepped parts being so proportioned and arranged and said back panels being so additionally relatively folded lengthwise of the tie that along a portion of the length of the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, and said second interlocking means incorporating a receptor established by a fold lengthwise of said second back panel and said second interlocking means also incorporating a complementary male element for entry into the last-named receptor, the last-named male element forming a part of said first back panel, each of said receptors being comprised wholly of a plurality of plies of the back panel which carries that receptor.

3. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped part of the other panel laterally of the tie whereby there are stepped parts in pairs across the width of the tie, said stepped parts being so proportioned and arranged and said back panels being so additionally relatively folded lengthwise of the tie that along a portion of the length of the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, said second interlocking means incorporating a receptor established by a fold lengthwise of said second back panel and said second interlocking means also incorporating a complementary male element for entry into the last-named receptor, the last-named male element forming a part of said first back panel, each of said receptors being comprised wholly of a plurality of plies of the back panel which carries that receptor, and each receptor presenting an open mouth which faces the fold between said face panel and the back panel which carries the other receptor.

4. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped

part of the other panel laterally of the tie whereby there are stepped parts in pairs across the width of the tie, said stepped parts being so proportioned and arranged and said back panels being so additionally relatively folded lengthwise of the tie that along a portion of the length of the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, said second interlocking means incorporating a receptor established by a fold lengthwise of said second back panel and said second interlocking means also incorporating a complementary male element for entry into the last-named receptor, the last-named male element forming a part of said first back panel, one of said receptors being established on the back panel which carries the same as the results of a Z-fold lengthwise of said panel.

5. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped part of the other panel laterally of the tie whereby there are stepped parts in pairs across the width of the tie, said stepped parts being so proportioned and arranged and said back panels being so additionally relatively folded lengthwise of the tie that along a portion of the length of the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, said second interlocking means incorporating a receptor established by a fold lengthwise of said second back panel and said second interlocking means also incorporating a complementary male element for entry into the last-named receptor, the last-named male element forming a part of said first back panel, one of said receptors being established on the back panel which carries the same as the result of a V-fold lengthwise of said panel.

6. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped part of the other panel laterally of the tie whereby there are stepped parts in pairs across the width of the tie, said stepped parts

being so proportioned and arranged and said back panels being so additionally relatively folded lengthwise of the tie that along a portion of the length of the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, said second interlocking means incorporating a receptor established by a fold lengthwise of said second back panel and said second interlocking means also incorporating a complementary male element for entry into the last-named receptor, the last-named male element forming a part of said first back panel, one of said receptors being established on the back panel which carries the same as the result of a V-fold lengthwise of said panel, the male element complementary to the last-named receptor being established on the back panel carrying said male element as the result of a V-fold lengthwise of said panel, whereby said male element may be hookingly engaged with the last-named receptor.

7. A necktie of the four-in-hand type, comprising a body portion shaped and folded to present a face panel, a first back panel folded in from one side of the face panel, a second back panel folded in from the other side of the face panel, each back panel along its free side edge in the region of a broad end of the tie being provided with a plurality of stepped parts, each stepped part of one back panel being opposite a stepped part of the other panel laterally of the tie whereby there are stepped parts in pairs across the width of the tie, said stepped parts being so proportioned and arranged and said back panels being so additionally relatively folded lengthwise of the tie that along a portion of the length of the tie coextensive with a first pair of said stepped parts a first interlocking means for the two back panels is provided, and along a portion of the length of the tie coextensive with a second pair of said stepped parts a second interlocking means for the two back panels is provided, said first interlocking means incorporating a receptor established by a fold lengthwise of said first back panel and said first interlocking means also incorporating a complementary male element for entry into said receptor, said male element forming a part of said second back panel, said second interlocking means incorporating a receptor established by a fold lengthwise of said second back panel and said second interlocking means also incorporating a complementary male element for entry into the last-named receptor, the last-named male element forming a part of said first back panel, there being auxiliary

means for quick detachable coupling of the receptor and the male element of an interlocking means.

8. A necktie of the four-in-hand type, comprising a body portion shaped for folding to present a face panel and a pair of side panels lying in back of said face panel so as to constitute back panels, said body portion between a part thereof to become the neckband of the tie and a broadened end of the tie, and along the free side edges of said side panels having stepped parts, said stepped parts in pairs laterally of the tie, one of said side panels having a stepped part opposite an unstepped part of the other side panel.

9. A necktie of the four-in-hand type, comprising a body portion shaped for folding to present a face panel and a pair of side panels lying in back of said face panel so as to constitute back panels, said body portion between a part thereof to become the neckband of the tie and a broadened end of the tie, and along the free side edges of said side panels having stepped parts, said stepped parts in pairs laterally of the tie, one of said side panels having a stepped part opposite an unstepped part of the other side panel, and said stepped parts being so placed that when one of said body portions is laid alongside another, with the latter upside down relative to the former, stepped parts on one of said body portions match stepped parts on the other of said body portions.

10. A necktie having a main section and a minor section cut from a single piece of sheet fabric from approximately parallel and adjacent portions of the fabric, the minor section having a diagonal end edge and the main section having a mating diagonal end edge, said diagonal end edges being joined to each other to secure the minor section in approximate axial alignment with the main section, the main section having cuts in its opposite longitudinal edges providing bendable edge strips, the main section having a front panel and side panels connected therewith, one of said side panels being double and carrying one of said bendable strips and the other side panel carrying a wider strip forming a back panel, the double side panels folding inwardly against the rear side of the front panel and said bendable strip carried thereby folding under the folded double side panels, the back panel folding between said bendable strip and said double side panels, and being secured to said bendable strip.
